UNITED STATES PATENT OFFICE.

MURRAY M. RAYMOND, OF CORRY, PENNSYLVANIA, ASSIGNOR TO THE RAYMOND MANUFACTURING COMPANY, OF SAME PLACE.

CHIMNEY-TOP.

SPECIFICATION forming part of Letters Patent No. 473,853, dated April 26, 1892.

Application filed October 19, 1891. Serial No. 409,192. (No model.)

To all whom it may concern:

Be it known that I, MURRAY M. RAYMOND, a citizen of the United States, residing at the city of Corry, in the county of Erie and State 5 of Pennsylvania, have invented certain new and useful Improvements in Chimney-Tops; and I do hereby declare the following to be a full, clear, and exact description of the invention, such as will enable others skilled in 10 the art to which it appertains to make and use the same, reference being had to the accompanying drawings, and to the letters of reference marked thereon, forming part of this specification.

15 My invention consists in the improvements in chimney-tops hereinafter set forth and explained, and illustrated in the accompanying drawings, in which—

Figure 1 is a perspective view of a chimney with my improved chimney-top in place thereon. Fig. 2 is a perspective view of my improved chimney-top ready to be placed upon a chimney. Fig. 3 is a perspective view 25 of one of the sections of the same, a portion thereof being broken away. Fig. 4 is a perspective view of a modified form of the sections of my improved chimney-top.

The object of my invention is to construct 30 a chimney-top of sections of like form and size bolted together, so as to form a complete top, these sections being of such size that a sufficient number of them secured together will form a top for any-sized chimney.

In the construction of my improved chimney-top shown in the drawings, A is a chimney, and B is my improved top thereon. This top B, I make of rectangular sections C, preferably cast of metal in the form of a hollow box or shell, or made of terra-cotta or other 40 suitable material and of like shape, these sections C being made twice as long as they

are wide and half as deep as they are wide—that is to say, of the same proportions as an ordinary brick. Centrally in the ends of each of the sections C, I make holes a, and in the 45 sides of each of the sections C, near one end thereof, I make holes d, these holes a and d being so located in the sections C that only one form and shape of section is required, of which a sufficient number of duplicates are 50 secured together by means of bolts D to complete the chimney-top, as illustrated in Fig. 2.

In place of the holes a and d, hereinbefore described, in the sections C, I can with equal facility use slots a' and d' therein, as illustrated in the modified construction shown in 55 Fig. 4.

Having thus fully described my invention, so as to enable others to construct and use the same, what I claim as new, and desire to secure 60 by Letters Patent of the United States, is—

1. A chimney-top section consisting of a hollow rectangular block having holes or slots in the sides of the block near one end thereof and also holes or slots in the ends thereof, substantially as and for the purpose set forth. 65

2. A chimney-top consisting of a series of hollow rectangular blocks or sections, as C, secured together at the sides and ends of the chimney by means of bolts, as D, passing 70 through holes or slots in the ends thereof, and at the corners of the chimney by bolts D, passing through holes or slots in the side of one block and in the end of the adjoining block, substantially as and for the purpose set forth. 75

In testimony whereof I affix my signature in presence of two witnesses.

MURRAY M. RAYMOND.
